UNITED STATES PATENT OFFICE.

LOUIS A. MILLER, OF NEW HAVEN, CONNECTICUT, ASSIGNOR TO WINCHESTER REPEATING ARMS CO., OF NEW HAVEN, CONNECTICUT, A CORPORATION OF CONNECTICUT.

HANDLAMP SWITCH.

Application filed July 15, 1921. Serial No. 484,844.

To all whom it may concern:

Be it known that I, LOUIS A. MILLER, a citizen of the United States, residing at New Haven, in the county of New Haven, State of Connecticut, have invented certain new and useful Improvements in Handlamp Switches; and I do hereby declare the following to be a full, clear, and exact description of the invention, such as will enable others skilled in the art to which it appertains, to make and use the same.

My invention is an improvement in the switches of battery hand lamps. In the usual construction of such handlamps, the circuit of the lamp is controlled by a switch usually including a push button supported in inoperative position by a spring, and adapted to be depressed to close the circuit. Unless care is exercised in the disposal of the lamp when not in use, the circuit may be accidentally closed, with consequent waste of current, and rapid exhaustion of the battery. In the use of such lamps, there is often occasion for a steady light, without attention on the part of the user. With the push button type of switch, which because of simple construction ease of operation and ability to withstand rough usage, is the preferred type, the switch must be held closed when a steady light is desired. The object of the present invention is to provide improved mechanism in connection with the switch by means of which the switch may be locked in either open or closed position, against possibility of accidental displacement.

In the drawings:

Figure 1 is a side view of a usual form of battery hand lamp.

Figure 2 is a plan view with parts in section.

Figures 3 and 4 are partial side views and with Figure 1, show the three positions of the switch locking mechanism.

Figures 5 and 7 are sections on the lines 5—5 and 7—7 of Figure 3.

Figure 6 is a section on the line 6—6 of Figure 4.

The present embodiment of the invention is shown in connection with a battery hand lamp of the vest pocket type, comprising a case 1 having at one end a socket 2 for receiving the bulb 3, and having at the other a hinged door 4 for permitting the insertion and removal of the battery indicated at 5.

The battery has contact plates 6 and 7, the former contacting with the bulb, while the other is adapted to be engaged by a switch, to be described, for closing the circuit through the lamp.

The switch includes a button 8 extending through an opening 9 in the case, and supported by a plate or leaf spring 10, rigidly secured at one end to the case as indicated at 11, and having at the other end a bearing opening, through which the button shank extends. The shank is provided with annular ribs 12 and 13 on opposite sides of the spring, for preventing displacement thereof, and the spring normally holds the button in outward position and out of contact with the contact plate 7. The circuit of the lamp is closed by depressing the button, to cause the inner end thereof to engage the contact plate 7 of the battery.

With this arrangement, when the hand lamp is placed in the pocket, for instance, or in any other position where the button might engage with another object, the button may be accidentally depressed, to close the circuit through the lamp. This results in rapid exhaustion of the battery. To prevent such waste of current, mechanism is provided for locking the switch in open position.

The said mechanism is in the form of a slide 14, having guided movement longitudinally of the case 1, and encircling the button. The slide, which is in the form of an escutcheon, is slidably connected with the case in any suitable manner, as for instance by lugs 15 at the sides of the slide, which extend through slots 16 in the case. The slide has a longitudinal slot or passage 17 through which the button extends, and this slot is of key hole shape as shown in Figures 1, 3 and 4. The widest portion of the slot is of a diameter corresponding substantially to that of the diameter of the button, while the narrowest part is of less width than the diameter of the button, and the button is annularly grooved as shown at 18 to permit the slide to move forward while the button is in its outer position. When the button is in the narrowest part of the slot, the opposite sides of the slot engage within the annular groove, effectively locking the button from movement in either direction, and when the button is depressed so that the slide will move over the button, the sides 19 of the narrower portion of the slot will move above 110

the button, and will prevent outward movement thereof. Such edges 19 may be considered as inwardly extending wings or fins at each side of the slot for engaging above 5 the button, or within the annular groove, to lock the same in desired position. The locking device may be operated by the thumb. With the parts in the position of Figure 1, the button is free to move inward or outward. To lock the switch in open position, it is only necessary to push the slide toward the bulb, this position of the parts being shown in Figures 3 and 5. The wings or fins 19 now enter the annular groove 18, and 15 the button is locked in open position. If for any reason it is desired to have a steady light, the button may be depressed, and with the same finger or thumb the slide may be slipped downwardly to bring the wings or 20 fins above the button, as shown in Figures 4 and 6. The switch is now locked in operative position, and the lamp will burn steadily until the switch is released. To unlock 25 in either position, it is only necessary to slide the plate inwardly.

My improved switch mechanism has been shown applied to a hand lamp of the flat or vest pocket type, but it will of course be understood that it is equally applicable to the 30 so-called tubular case and to cases of other design.

I claim:

1. A contact device for battery hand lamps, comprising a spring controlled push button manually operable from open-circuit 35 to closed-circuit position, and a slide movable longitudinally of the lamp surrounding said push button and adapted to engage the upper surface of said push button when in 40 closed circuit position, to retain the same in such position, said push button having a single groove engageable by said slide when said push button is in open circuit position to retain the same in such position, said push 45 button and slide being arranged so that they

may be actuated as desired by the thumb of one hand alone.

2. A contact device for battery hand lamps, comprising a leaf spring, a push button mounted thereon, and a slidable locking member having a keyhole slot adapted to 50 contact with the top of said push button, said push button having a single circumferential groove adapted to be engaged by the edges 55 of the slot in the locking member, said push button and locking member being arranged so that they may be actuated as desired by the thumb of one hand alone to flash the lamp by pressing the push button through 60 the large portion of the keyhole slot, and to lock the push button in closed circuit position or in open circuit position by moving the slide until the edges of the keyhole slot engage the push button, substantially as described. 65

3. A contact device for battery hand lamps, comprising a slide in the form of an escutcheon arranged for guide! movement longitudinally of the lamp casing and having a keyhole slot therein, a leaf spring fixed 70 at one end to the hand lamp casing, a push button mounted on the free end of the spring and extending through the hand lamp casing and the keyhole slot in the slide, said push button having a single groove engageable by the narrow portion of said keyhole slot, said push button and slide being arranged so that they may be readily manipulated as desired by the thumb of one hand alone, to flash the lamp, to press the push 75 button into closed circuit position and move the slide over the top thereof, to move the slide until the narrow portion of the slot therein engages the groove in the push button, or to release the push button after it has been locked in open or closed circuit position. 80

In testimony whereof I affix my signature.

LOUIS A. MILLER.
